(57) CLAIM

The ornamental design for a TV stand, as shown and described.

DESCRIPTION

FIG. 1 is a front top perspective view of the TV stand of the present invention showing our new design;

FIG. 2 is an end elevational view thereof; and,

FIG. 3 is a front elevational view thereof.

The surface(s) or portion(s) of the article not shown in the drawing or described in the specification form(s) no part of the claimed design.
